LIFT TRUCK

Evan E. Dorkins, Ottawa, Kans., assignor to L. A. Young
Spring and Wire Corporation, Detroit, Mich., a cor-
poration of Michigan

Application February 16, 1956, Serial No. 40,183

Term of patent 14 years

(Cl. D14—3)

Fig. 1.

Fig. 4.

Fig. 2.

Fig. 3.

Fig. 5.

Fig. 1 is a perspective view of a lift truck embodying my new design taken from the rear and one side thereof;

Fig. 2 is a perspective view of the lift truck taken from the opposite side of Fig. 1;

Fig. 3 is a rear elevation of the lift truck;

Fig. 4 is a fragmentary side elevation; and

Fig. 5 is a top plan view of the full line portions shown in Figs. 1 through 4.

The dominant features of my design reside in the portions shown in full lines.

I claim:

The ornamental design for a lift truck, as shown and described.
